ELECTRIC SIGNALING SYSTEM

Edward Albert Henry Bowsher, Harold Mountjoy Muschamp d'Assis-Fonseca, and Hugh Jennings Ward, London, England, assignors to Standard Telephones and Cables Limited, London, England, a British company

Application April 19, 1945, Serial No. 589,245
In Great Britain March 31, 1944

Section 1, Public Law 690, August 8, 1946
Patent expires March 31, 1964

6 Claims. (Cl. 177—353)

1

This invention relates to electric signalling systems and more particularly to electric remote control and supervisory systems.

British patent specification 514,991 describes an electric signalling system invented by one of the present applicants in which a control station and a selected substation can be connected together on a party line common to a number of substations, and in which hold signals are continuously transmitted alternately in opposite directions over the party line so that the control station and selected substation are held connected to the line to the exclusion of other substations to which the line is also available when idle.

That invention was described as being applicable to a system which comprised a control station and a number of party-line substations, each station including a signal sender and a signal receiver. When the system is at rest, communication between the control station and any substation can be initiated by either of them. In the first case the control sends out a signal distinctive of the one substation desired, and this signal, although received by all the substations, is effective only at that one. Further identity checking and like signals may be exchanged between the two interconnected stations; but eventually the substation will send back signals descriptive of the condition of each apparatus unit, e. g. circuit breaker, in the substation. In the second case, some occurrence in an apparatus unit in any one substation, e. g. the tripping of a circuit breaker, automatically causes the substation to send a signal to the control, and again, with or without a further exchange of signals, the substation will send signals descriptive of the condition of the apparatus units. Furthermore, this same party-line is used for the sending of control signals from the control station to any one apparatus unit in any one substation, for the purpose of changing or confirming its condition or position.

The signal sender and signal receiver in each station are so interlocked that the sender cannot function whilst the receiver is functioning. In consequence, so long as there continues on the line the "shuttlecock" operation already mentioned as being the main feature of the invention described in the aforesaid British patent specification No. 514,991, all the other substation senders are paralyzed.

The impulses sent in both directions during shuttlecocking are of short duration. When, however, the engineer at the control station

2

wishes to effect a certain control at the substation, he causes the pulses from the control station to be modified. In the prior case above referred to this modification consisted of a lengthening of a single pulse; in the present invention on the other hand means are provided so that at least two consecutive long pulses must be received to effect the control.

One of the advantages of the arrangement in accordance with the present invention is that it makes the operation of a signalling system as described more reliable and less subject to upset from extraneous causes. Thus where the control signal consists of one long pulse only, it might be simulated by the application of a battery to the line or the induction of an electromotive force therein in any accidental manner; the present invention therefore uses a plurality of long pulses as the control signal and the control circuit is designed to respond only to such signals.

Another advantage of the arrangement in accordance with the present invention is that it enables the engineer at the control station to maintain the control for as long as he deems it necessary. The apparatus to be controlled, such as circuit breakers, may have different operating times, but no matter how slow they may be, the engineer can maintain control of that apparatus until he gets the indication back that the control has become effective.

The description that follows relates to the accompanying drawing, in which:

Fig. 1 shows the circuit of the equipment at the control station for the control and supervision of the several apparatus units at a substation; and

Fig. 2 shows the circuit of the corresponding equipment at a substation.

In reading the following circuit description, it will be understood that all relays are shown on the drawing in their normal unoperated condition. The relays are designated by capital reference letters accompanied by a figure indicating the number of relay armature contacts associated with that relay, the relay armature contacts being designated by corresponding small reference letters and a number indicating the particular contact involved. For example, in Fig. 2 relay SAS has seven contacts and is shown as SAS/1 and these contacts are designated *sas1*, *sas2*, *sas3*, *sas4*, *sas5*, *sas6*, *sas7*. These contacts are not shown adjacent to the relay to which they belong, but are arranged in the circuits controlled by them, thus considerably simplifying the drawing and facilitating the tracing of

the various circuit operations. In describing a circuit connection, the word "up" following a contact designation indicates that the relay is operated, whereas the designation alone indicated that the relay is normal; e. g., referring again to Fig. 2, the circuit line L₁, pss₁ up, sas₁, polarised relay SP, sas₂, pss₂ up, line L₂; indicates that PSS is operated, but SAS normal.

GENERAL DESCRIPTION

The control station shown in Fig. 1 and a plurality of substations like that shown in Fig. 2 are connected to a common two-wire line L₁, L₂. An individual connection between the control station and any one substation can be set up to the exclusion of all the other substations and can be maintained so long as necessary; this setting up can be initiated either from the control station or from the substation. At CSC in the control station, and SSC in the substation are indicated known selection circuits by means of which signals can be sent and received for the purpose of selecting firstly a particular substation from among those on the common line and secondly a particular apparatus unit from among those in the particular substation, the latter selection involving a setting of the stepping switches indicated by the wipers SPC₁ and SPC₂ in the control station and SPS₁, SPS₂, and SPS₃ in the substation. Each selection circuit includes a signal sender and a signal receiver so interlocked that the sender cannot function whilst signals are incoming to its associated receiver. Once an individual connection has been set up between the control station and a particular substation, that connection is maintained and other stations excluded by the continuous exchange of signals between the two stations over the line in the manner disclosed in the patent specification No. 514,991 above referred to. The signals from the control station are single short negative pulses, while the signals from the substation are single short pulses that are positive or negative according as the particular circuit breaker is at the time closed or open. Thus the polarity of the signals sent from the substation during shuttlecocking furnishes a supervisory indication at the control station of the condition of the selected circuit breaker because the appropriate indicating lamp will be lit at the control station.

When the engineer at the control station desires to change-over the circuit-breaker, he depresses the close key CK or the trip key TK, as the case may be. Then, so long as the key is held down, the short negative pulses from the control station are replaced by long pulses that are either positive or negative according as the control is that of closing or opening. The substation pulses continue short, but will be reversed in polarity as soon as the breaker has actually changed over.

Before describing the detail circuits, the following brief description of the sequence of operations will assist in a better understanding of the invention and of the novel features involved. Thus, after selection of the desired substation and the particular circuit breaker at the substation, the following sequence occurs: Relays PSC at control and PSS at substation operate and at contacts psc₁, psc₂, and pss₁, pss₂ switch the line L₁, L₂ from the selection circuits CSC and SSC to the polarised pulsing arrangements. Relay SA at the control station operates momentarily and at contacts sas₁, sas₂ connects negative feed line to line L₁, the negative pulse thus transmitted causing operation of polarised relay SN

at substation. This operates slow release relay PGS and when SN releases at cessation of feed controlled by SA, relay SAS operates and at contacts sas₁, sas₂ switches the line L₁, L₂ at the substation from the polarised relays to the feed. The pulse thus transmitted from the substation, which is negative if the circuit breaker is in the tripped position, and positive if the circuit breaker is closed, operates polarised relay CN or CP at the control station, thus causing operation of slow release relay PGC and supervisory relay OL which controls the "Red" and "Green" indicating lamps, the green lamp indicating that the circuit breaker is tripped and the red lamp that it is closed. Operation of PGC causes operation of relay SA as soon as the polarised relay CN or CP falls off at the cessation of the pulse from the substation, and relay SA at its contacts sas₁, sas₂ again connects negative feed to the line and the same sequence of operations is repeated. It will thus be seen that relay SA at the control station and relay SAS at the substation are the relays which control the transmission of shuttlecock pulses between the control station and a selected substation. These relays also control the long control pulses as will be seen later.

When the engineer at the control station wishes to close a circuit breaker at the substation, he presses his "close key" CK and this has the effect of energising relays CR and TL. Relay CR at contacts cr₁, cr₂ changes the feed on the line to positive, and relay TL at contact tl₁ prepares a locking circuit for relay SA so that this relay will be held operated to send a long pulse, and as contact cr₁ has connected positive potential to line L₁, a long positive pulse is sent to the substation. The duration of this pulse is determined by the successive release times of the two slow-release relays PGC and PGL as PGL is controlled by PGC and PGL has a contact pgl₁ in the locking circuit of SA and thus SA is maintained operated until both PGC and PGL release.

The effect of this long positive pulse at the substation is to operate polarised relay SP and hold it operated for the duration of the pulse thus preventing relay SAS from operating quickly as it did for the shuttlecock pulsing and this allows the slow release relay SAR, which is controlled by SAS, to release and allow relays X and Y to operate. The operation of these relays causes the operation of relays CRS and LP which at contacts crs₁ and lp₈ prepare the operating circuit for the "close magnet" CC for the circuit breaker. When the long pulse ceases, polarised relay SP releases and allows SAS to operate, and this, as previously described, sends a short negative pulse to the control station which will be indicated by the lighting of the green lamp as the circuit breaker is still tripped. It will be observed that the effect of the first long pulse at the substation was merely to prepare the circuit for the "close" magnet CC but this magnet did not operate at this time as its circuit was broken at x₁ and y₁. It will also be observed that operation of relay SAS reoperated slow release relay SAR with the result that relay X released at sar₃. At the cessation of the negative pulse from the substation, polarised relay CN at the control station falls off and relay SA reoperates. As the "close key" CK is still depressed another long positive pulse will be sent. Relays CRS and LP remain operated over locking circuits, so that this time when slow release relay SAR releases, it will cause the release of relay Y by opening the circuit at sar₃. With relays X and Y now released and CRS and

LP still operated, the circuit for "close" magnet CC is completed over wiper SPS3, *crs1* up, *y1*, *x1*, *lp8* up to positive battery. The circuit breaker closes and operates the "breaker contact" IC to close the contacts *C1*, *C2*, thus operating relay JB over the wiper SPS1. Relay JB operates relay PP which at contacts *pp1* and *pp2* reverses the feed and the next pulse from the substation will be positive. A positive pulse at the control station operates polarised relay CP which operates the latching winding L of relay OL to light the "red" lamp. These operations are repeated automatically as long as the "closed" key CK is depressed, but the lighting of the "red" lamp indicates to the control engineer that the circuit breaker at the substation is closed, and he would then release the key.

Operation of the "trip" key TK results in a similar series of operations but in this case long negative control pulses will be sent as relay CR does not operate. At the substation polarised relay SN operates, and instead of relay CRS, the relay TLS will operate with LP, and thus the operating circuit for the "trip" magnet TC is prepared at *tls1* and this magnet will operate in the circuit over wiper SPS2, *tls1* up, *y1*, *x1*, *lp8* up when relays X and Y release as previously described. Breaker contact IC opens the circuit of relay JB which releases relay PP with the result that the supervisory pulse from the substation will be negative. This causes operation of polarised relay CN at the control station with the result that the unlatching winding U of the supervisory relay OL is operated and the "green" lamp is lit, thus indicating that the circuit breaker has tripped.

DETAILED DESCRIPTION

Setting up and holding a connection

The engineer at the control station, desiring to set up a connection to a particular substation, transmits a set of impulses from CSC over the party line *L1*, *L2*, to the receiving equipments in the selection circuits SSC at all the substations. This set of impulses selects the one substation only. Then a further set of impulses is transmitted from CSC, this time being determined by the setting of switch wipers SPC1 and SPC2 and having the purpose of selecting a particular piece of apparatus such as a circuit-breaker in the said substation. The switch wipers SPS1—SPS3 in the substation circuit SSC are thus positioned on an outlet unique to that piece of apparatus. Provision may or may not be made to send back to the control station a signal confirmatory of the actual position of the selector wipers SPS1—SPS3; in any case at the end of such selection signal the selection circuits CSC at the control station and SSC at the substation will cause the operation of their respective relays PSC and PSS.

At the same time in the control station the selection circuit CSC applies a short-circuit across contacts *pgc1* as indicated by the dotted line A so that as a result of the operation of relay PSC, relay SA is operated in a circuit: positive battery *psc3* up, *cn1*, *cp1*, the CSC shunt A, winding of relay SA to negative battery. The contacts *sa1* and *sa2* are arranged to give alternative connections of the line *L1*, *L2*, either to a battery feed for sending signals to the substation, or to a pair of relays CN and CP for receiving similar signals from the substation. Thus when SA operates, a feed is applied to the line from negative over resistance *YC*, contacts *cr1*, *sa1* up, *psc1* up,

to wire *L1*, and from positive over contacts *cr2*, *sa2* up, *psc2* up to wire *L2*. A feed of this polarity, negative on *L1* and positive on *L2*, is for convenience designated a negative feed, whereas positive on *L1* and negative on *L2* is designated as positive feed. The operating circuit for relay SA is maintained by the shunt A in CSC for a short period only, after which SA releases and takes the negative feed off the line by opening the contacts *sa1* and *sa2*.

At the substation, Fig. 2, the feed is applied to the oppositely polarised relay bridge SN, SP over the operated contacts *ps1* and *ps2*, it being remembered that relay PSS operated at the end of the substation selection signal. The feed being negative it causes relay SN to operate, in turn operating slow release relay PGS from positive battery *ps6* up, *sn1* up, left-hand winding of PGS. When the feed is taken off due to the release of relay SA in the control station, relay SN releases, and relay SAS operates; from positive battery over *ps6* up, *sn1*, *sp1*, *pgs1* up, *lp5*, winding of relay SAS to negative. Contacts *sas1* up and *sas2* up apply to the line a feed which may be either positive or negative as will appear below. At the same time the release of SN has opened the operating circuit of relay PGS, and this relay slowly releases, its delay period determining the duration of the feed to the line because the operating circuit for relay SAS over whose contacts *sas1* and *sas2* the feed is applied, includes the contact *pgs1* of relay PGS.

The control station responds to the feed applied at the substation with the operation of polarised relay CN or CP, according to the feed polarity, in either case operating the slow-release relay PGC from battery *psc3* up, and either *cn1* up, or *cp1* up to the right or left hand winding of relay PGC. When the feed is taken off the line by the release of relays PGS and SAS (Fig. 2), so that CN (or CP) releases, relay SA operates: battery *psc3* up, *cn1*, *cp1*, *pgc1* up, winding SA; the operation of relay SA disconnects the polarised relay bridge CN, CP from the line at contacts *sa1* and *sa2*, and re-applies negative feed as before described. At the same time the release of CN (or CP) has opened the operating circuit of relay PGC, and this relay releases slowly, its delay period determining the duration of the feed to the line by virtue of its control of relay SA.

This cycle of operation, consisting of a pulse in each direction, and repeating itself until release of either relay PSS at the substation or PSC at the control station, is the "shuttlecocking" disclosed in our above-mentioned patent specification and is the means whereby the line is held by the one substation to the exclusion of the others.

Utilisation of the substation signals for supervision

It has been stated above that those shuttlecock signals originating at the substation might be of either polarity. This polarity depends upon the condition of the circuit breaker or other apparatus that has been selected by the positioning of switch SPS. As shown in Fig. 2, the circuit breaker selected has a pair of auxiliary contacts *ck* and *c2* which are closed or opened by the armature IC associated with the circuit breaker, which is not shown in the drawing, according to the circuit breaker condition. One of the contacts *c1* is connected to the appropriate contact in the bank of the selector associated with wiper

SPS1. The wiper SPS1 leads to the relay JB, via contact *pss4* and relay JB is thus operated or not operated by armature IC according to the breaker condition. Relay PP follows the movements of JB, operating or releasing as that relay operates or releases contact *jb2* but only when relay SAS is released to close the back contact *sas4*.

At the control station, where either relay CN or CP responds, positive potential is applied either to wiper SPC1 or SPC2 of the selector over the contact *cn1* or *cp1* respectively. To the banks of the selector associated with these wipers, on outlets corresponding to the breakers at the substation, are connected the latching and unlatching windings marked L and U respectively of mechanically latching relay OL. Thus the latching relay OL follows the movement of the corresponding circuit breaker, and its contacts *ol1* lights one or other of a pair of lamps marked "green" and "red" respectively to give a visual indication on the control board of the breaker condition.

Circuit breaker control

Before proceeding with the description of the operation of closing a breaker, it should be pointed out that when SAS and SA first operated at the substation and control station respectively, slow release relays SAR and SR were also operated over obvious circuits including contacts *sas1* and *sa4* respectively. At the substation this resulted in operation of relay X; from positive battery, *pss5* up, *sar3* up, *y4*, *lp6* left hand winding of relay X to negative; and at the control station in the maintenance of relay PSC over *sr1*. At the control station also, the first operation of relay PGC brought up the slow-release relay PGL over contact *pgc2* which prepared a locking circuit for relay SA over contact *pgl1*.

When the selected breaker is to be closed or tripped the appropriate non-locking close or trip key CK or TK is depressed.

Closing a breaker

Key CK is depressed and when relay SA first releases at *pgc1* as previously described the relay CR operates; *psc4* up, *sa5*, CK closed, CR; and brings up relay TL over contact *cr3*. Relay CR by its contacts *cr1* and *cr2* reverses the polarity of the feed that will be offered to the line when next SA operates. Contacts *tl1* complete the preparation of the locking circuit of relay SA, so that when this relay next operates it locks; *psc3* up, *cn1*, *cp1*, *pgl1* up, *tl1* up, *sa3* up, SA; thus maintaining the feed to the line beyond the short time pulses previously described for shuttle-cocking. Relay PGC is meanwhile releasing slowly and finally falls off, thus starting the slow release of relay PGL whose contact *pgl1* is in the locking circuit of SA. Throughout the successive release times of PGC and PGL relay SA remains up, so that the feed to the line is not only of positive polarity but is of lengthened duration.

At the substation polarised relay SP operates in response to the long positive pulse, and relay SAS is prevented, at contact *sp1* up from operating for a longer time than hitherto, sufficiently long for slow-release relay SAR to drop off and operate relay X in the circuit from positive, *pss5*, *sar3*, *lp6* to X. Operation of relay X closes the circuit for relay Y at *x5* and relay Y operates in the circuit; *pss5* up, *sar3*, *x5* up, Y. With both relay X and relay Y now operated relays

LP and CRS operate; *pss6* up, *sn1*, *sp1* up, *x3* up, *y3* up, left-hand winding of LP, or *tl2*, left hand winding of CRS. These relays lock in the following circuit; middle winding of LP, *lp4* up, *sar2*, *pss7*; and right-hand winding of CRS, *crs3* up, *lp1* up. With the operation of CRS a circuit is prepared for the close contactor magnet CC over contact *crs1*.

Ultimately, when the positive feed is taken off the line, relay SP releases, and relay SAS operates in the following circuit; *pss6* up, *sn1*, *sp1*, *pgs1* up, *sar1*, SAS; relay SAR operates over *sas1* up. Operation of relay SAR releases relay X at contact *sar3* up but leaves Y up. The operation of SAS applies negative feed to the line over contacts *sas1* and *sas2* for a short period determined, as before, by the release time of PGS.

At the control station relay CN responds to the negative feed, bringing up relays PGC and PGL as before, and energising the unlatching winding U of relay OL via SPC1 wiper and bank. Contacts *ol1* in the unlatched position light the green lamp. At the end of the feed from the substation, relay CN releases and, relay SA operates and locks, applying a positive feed to the line for a lengthened period determined as before by the slow-release times of relays PGC and PGL in succession.

At the substation, as before, relay SAS remains 30 inoperative during the long positive pulse, so that again SAR releases. This time relay Y releases, and completes a circuit to the closing contactor CC; *lp8* up, *x1*, *y1*, *crs1* up, SPS3, CC.

This cycle of operations, consisting of short 35 pulses from the substation and long positive pulses from the control station, will be repeated so long as the close key CK is held down at the control station. At the substation relay LP will hold, and will prevent the repeated operation and 40 release of SAR from operating relay X which in turn keeps relay Y unoperated; also contacts *lp1* up will maintain relay CRS operated and this in turn maintains the operating circuit for the closing contactor CC.

45 When the circuit-breaker closes, the armature IC closes the contacts *c1* and *c2* and relay JB operates in an obvious circuit over SPS1 and *pss4* up. Upon the next release of SAS therefore, relay PP operates and locks over *jb2* up, reversing at contacts *pp1* and *pp2* the polarity of the subsequent pulses from the substation. This reversal of polarity is effective at the control station to operate relay CP instead of CN, thus energising the latching winding L of the relay OL over SPC2, *cp1* up, *cn1*, *psc3* up and lighting the red lamp instead of the green at contact *ol1*.

On receiving this indication that the circuit breaker has actually closed, the engineer releases key CK, so that on the next release of SA, relays 60 TL and CR release. Relay CR at contacts *cr1* and *cr2* restores the polarity of the signalling feed to negative, while relay TL at contacts *tl1* opens the holding circuit for SA that extends over *pgl1*, so that the duration of subsequent impulses 65 from the control station is restored to normal, being determined by the release time of relay PGC only.

At the substation, relay SN responds to the negative pulses, but now relay SAS is held inoperative for a time insufficient to cause the release of slow release relay SAR, so that at the end of the first short pulse relay SAS is unable to operate in the usual way owing to the break in its circuit at *sar1* up. Also relay LP releases, 75 its one holding circuit being opened at *sn1*, and

its other holding circuit opened at $sar2$ up, $sas6$, and $pgs2$ up. Relay CRS releases at $lp1$, releasing the contactor CC at $crs1$. The operating circuit of SAS is closed at $lp5$, and the normal shuttlecock working is restored as described above.

Tripping a breaker.

Considering now the alternative control, that of tripping a breaker, this is to be done by depressing the trip key TK. The operations are then similar to those already described, except that the polarity of the lengthened pulses sent from the control station is negative, relay CR not being operated.

At the substation those lengthened pulses cause operation of relay TLS instead of CRS, and during the second of such pulses the tripping contactor TC is operated; $lp8$ up, $x1$, $y1$, $tls1$ up, $SPS2$, TC. The breaker trips, moving armature IC and opening contacts $c1$ and $c2$, and thus releasing relay JB; so that when the relay SAS next releases, relay PP also releases, at $jb2$, reversing the polarity of subsequent impulsion from the sub-station at contacts $pp1$ and $pp2$.

At the control station, relay CN responds, energising the unlatching winding U of relay OL over $cn1$, and lighting the green lamp instead of the red.

It will thus be seen that long pulses from the control station persist so long as the control key CK or TK is held down, and that the effect of this at the substation is to maintain the contactor magnet CC or TC operated similarly. Thus the contactor magnet can be held operated for a sufficiently long time to allow for the slowest-operating piece of apparatus controlled thereby to operate. The short pulses from the substation at all times indicate the position of the breaker, and thus give the engineer positive and instant information enabling him to determine quite certainly how long to hold the key down.

It will be noted also that, once operated, relay JB cannot release until both relay PP and relay SAS are operated; and that PP cannot operate or release while relay SAS is operated because in the one case its operating circuit over $jb2$ is broken at $sas4$ up, and in the other case its locking circuit is maintained over $pp4$ and $sas4$ up. Thus, if the breaker is closed on to a fault and immediately trips, relay JB operates as previously described and locks until the next operation of SAS, while relay PP, having already operated over $jb2$ up, when SAS was unoperated, is held operated in its locking circuit over $pp4$ until SAS releases. The pulse sent at this time is positive, indicating the closed condition, so that provided the breaker has closed its auxiliary contacts $c1$ and $c2$ by armature IC, for no matter how short a period, a "closed" indication pulse of normal duration is sent back to the control station.

With both PP and SAS operated the locking circuit of relay JB is opened at $pp3$ and $sas3$ and, if the breaker has tripped, JB releases as its lower winding circuit is broken at the auxiliary contacts $c1$ and $c2$. When next SAS restores, PP also releases at $jb2$ so that the negative feed circuit is prepared at $pp1$ and $pp2$, and subsequent pulses transmitted by SAS are of negative polarity, indicating the open condition of the breaker. Thus the engineer is clearly informed that the breaker was closed on to a fault and tripped immediately.

Incomplete control operation

The period during which the pulses from the

control station are lengthened, is governed by the time for which the Close key or Trip key is depressed. If the key is depressed for a period sufficient only for one long pulse to be transmitted, the subsequent short pulses reset the discriminating relays at the substation as follows:

The single long pulse results in the operation of relays Y, LP, and CRS (or TLS), and, at the termination of this pulse, release of relay X as previously described.

The complete control can only be effected by the release of relay Y while relays LP and CRS (or TLS) remain operated, which condition is achieved normally by the release of relay SAR on the second long pulse. In this case as the key CK or TK has been released, the second and following pulses are replaced by short pulses, and slow release relay SAR does not release, so that relay SAS is unable to operate in the usual way, at the termination of the long pulse, owing to the break in its circuit at $sar1$ up. Also relay LP releases, its one holding circuit being opened at $SP1$ (or $SN1$) and its other holding circuit opened at $sar2$ up, $sas6$, and $pgs2$ up. Relay CRS (or TLS) releases at $lp1$ and relay Y releases at $lp7$. Relay X now operates over its original operating circuit $pss5$, $sar3$, and $lp6$, and the whole circuit is returned to the normal shuttlecock condition.

Interfering long pulse

If an interfering long pulse is imposed on the line from some external source this results in releasing relay SR at the control station and relay SAR at the substation because the appropriate polarised relays will be operated and prevent the shuttlecock relays SA and SAS from operating normally. Release of SR causes relay PSC to release, breaking down the shuttlecock circuit at the control station because the line is disconnected at $psc1$ and $psc2$ from the polarised relays.

At the substation the long pulse results in the operation of relays X and Y, relay LP and relay CRS (or TLS) as described above, and at the termination of the pulse, a short pulse is sent to the control station in the normal manner. In this case, however, as the control shuttlecock circuits are disconnected, the pulse has no effect, and no further pulses are sent to the substation. Thus PGS remains unoperated and relay PSS releases slowly, disconnecting the substation shuttlecock circuit at contacts $pss1$ and $pss2$, and reconnecting the selection circuit to the line.

What is claimed is:

1. In a remote control and supervisory system comprising a control station and a substation on a party line, with means for the transmission of electric pulses of short duration alternately from the control station to the substation and from the substation to the control station, and for operating a control magnet at the substation by the transmission of an electric pulse of longer duration, the combination with said control magnet of a circuit comprising a plurality of relay contacts, a plurality of relays for controlling said contacts, relay means controlled by said impulses and having contacts arranged to prevent operation of said plurality of relays during receipt of impulses of short duration, said relay means being effective on receipt of an impulse of long duration to cause operation of said plurality of relays to close certain of said relay contacts in the control magnet circuit, means operative on cessation of said pulse of long duration to transmit a short supervisory pulse to the control station, means at the control station operated by said

supervisory pulse to cause operation of an indicating device and operative on cessation of said supervisory pulse to cause the transmission of a second pulse of long duration, means at the substation responsive to said second pulse to cause said plurality of relays to close all the relay contacts in said control magnet circuit, means controlled by the operation of said control magnet to change the nature of the next supervisory pulse to be transmitted from the substation, means operative on cessation of said second pulse to transmit said supervisory pulse to operate said indicating device, and manually operable means at the control station to cause the transmission of a further pulse of long duration if the said indicating device operated by said supervisory signal indicates that the required operation has not been effected.

2. A remote control and supervisory system according to claim 1, wherein said plurality of relays includes two pairs of relays, each relay of each pair having a contact in the control magnet circuit, and wherein contacts of one pair of relays control the operation of the relays in the other pair, and wherein said relay means controlled by the pulses causes operation of said first pair of relays on receipt of a first pulse of long duration to cause successive operation of said relays of the other pair to close said contacts in the control magnet circuit, said relay means operating on cessation of said pulse to release one of said relays of the first pair to close its contact in the control magnet circuit and re-operating on receipt of a second pulse of long duration to release the other relay of the pair to close its contact in the control magnet circuit, whereby the control magnet circuit is closed only after receipt of at least two pulses of long duration to operate said relay pairs in sequence.

3. A remote control and supervisory system according to claim 1, wherein the transmission of pulses from the control station is controlled by a relay device arranged in a circuit including contacts of a slow release relay and an auxiliary locking circuit including a contact operated by a control key, and contacts of a second slow release relay controlled by said first slow release relay, whereby said relay controls the transmission of pulses of long or short duration, depending on whether the control key is operated or unoperated to close or open said locking circuit, and whereby the duration of each pulse of short duration is controlled by the release time of said first slow release relay, whereas the duration of each pulse of long duration is controlled by the successive release times of both said slow release relays.

4. A remote control and supervisory system according to claim 1, wherein the transmission of pulses from the control station is controlled by a relay device under control of pulses received from the substation and wherein said relay device actuates a slow release relay, adapted to remain energised during short releases of said relay device, said slow release relay being adapted to cause release of the control station circuit when de-energised as the result of an interfering pulse of long duration being imposed on the line.

5. In a remote control and supervisory system comprising a control station and a substation on a party line, with means for the transmission of electric pulses of short duration alternately from the control station to the substation and from the substation to the control station, and for operating a control magnet at the substation by the transmission of an electric pulse of longer dura-

tion, the combination with said control magnet of a circuit comprising a plurality of relay contacts, a plurality of relays for controlling said contacts, relay means controlled by said impulses and having contacts arranged to prevent operation of said plurality of relays during receipt of impulses of short duration, said relay means being effective on receipt of an impulse of long duration to cause operation of said plurality of relays to close certain of said relay contacts in the control magnet circuit, means operative on cessation of said pulse of long duration to transmit a short supervisory pulse to the control station, means at the control station operated by said supervisory pulse to cause operation of an indicating device and operative on cessation of said supervisory pulse to cause the transmission of a second pulse of long duration, means at the substation responsive to said second pulse to cause said plurality of relays to close all the relay contacts in said control magnet circuit, means controlled by the operation of said control magnet to change the nature of the next supervisory pulse to be transmitted from the substation, and means operative on cessation of said second pulse to transmit said supervisory pulse to operate said indicating device.

6. In a remote control and supervisory system comprising a control station and a substation on a party line, with means for the transmission of electric pulses of short duration alternately from the control station to the substation and from the substation to the control station, and for operating a control magnet at the substation by the transmission of an electric pulse of longer duration, the combination with said control magnet of means effective on receipt of an impulse of long duration to condition the control magnet circuit, means operative on cessation of said pulse of long duration to transmit a short supervisory pulse to the control station, means at the control station operated by said supervisory pulse to cause operation of an indicating device and operative on cessation of said supervisory pulse to cause the transmission of a second pulse of long duration, means at the substation responsive to said second pulse to close said control magnet circuit, means controlled by the operation of said control magnet to change the nature of the next supervisory pulse to be transmitted from the substation, and means operative on cessation of said second pulse to transmit said supervisory pulse to operate said indicating device.
